US0D1055097S

(12) **United States Design Patent** (10) **Patent No.:** **US D1,055,097 S**
(45) **Date of Patent:** **** Dec. 24, 2024**

(54) **DISPLAY SCREEN WITH ICON**

(71) Applicant: **Altria Client Services LLC**,
Richmond, VA (US)

(72) Inventors: **Terry Bache**, Richmond, VA (US);
Ryan McGinley, St Neots (GB); **Nicola Westgarth-Flynn**, St Neots (GB); **Eric Hawes**, Midlothian, VA (US);
Raymond W. Lau, Glen Allen, VA (US); **Zack W. Blackmon**, Richmond, VA (US)

(73) Assignee: **Altria Client Services LLC**,
Richmond, VA (US)

(**) Term: **15 Years**

(21) Appl. No.: **29/853,722**

(22) Filed: **Sep. 19, 2022**

(51) **LOC (14) Cl.** **14-04**

(52) **U.S. Cl.**

USPC **D14/489**; D14/492
